UNITED STATES PATENT OFFICE.

FREDERICK A. DURBIN, OF EVANSVILLE, INDIANA, ASSIGNOR OF ONE-HALF TO
JOSEPH F. MADAY, OF EVANSVILLE, INDIANA.

PERMUTATION PADLOCK.

1,423,840.

Specification of Letters Patent. Patented July 25, 1922.

Application filed May 18, 1921. Serial No. 470,635.

To all whom it may concern:

Be it known that I, FREDERICK A. DURBIN, a citizen of the United States, residing at Evansville, in the county of Vanderburgh and State of Indiana, have invented certain new and useful Improvements in Permutation Padlocks, of which the following is a specification.

This invention relates to permutation padlocks of that general class having a slideable shackle provided with notches and tumbler rings adapted to be turned into said notches to lock the shackle, or, when properly relatively set to carry out the combination, to release the shackle by virtue of the registry therewith of notches in the rings.

My improvements relate, more particularly, to the provision of a novel combination of shackle and body by which the shackle is prevented from pulling out completely and becoming lost but which permits the shackle to be slid when the proper combination of tumbler rings has been brought about.

The invention also consists in the general novel combination and relationship of body, tumbler rings, and shackle as set forth fully hereinafter.

The novel features and combinations residing in the invention are recited in the appended claim.

In the accompanying drawings:

Figure 1 is a side elevation, the shackle being locked.

Fig. 2 is a vertical section with the parts in the condition showing the shackle unlocked, and in full lines before being drawn out, dotted lines representing the manner in which the shackle can be swung on its joint.

Fig. 3 is a vertical section showing the shackle locked.

Fig. 4 is a section on line 4—4 of Fig. 2.

Fig. 5 is a section on line 5—5 of Fig. 2.

Fig. 6 is a section on line 6—6 of Fig. 3; and

Fig. 7 is a detail elevation of the body with parts broken away to illustrate the socket which receives the inner end of the shackle, the head of the body being removed.

The cylindrical body 1 is provided with a head 2 which may be pinned or secured thereto in any suitable manner. Along one side of the body extends a groove 3 which is in line with a pocket 4 and which is intersected by a groove or chamber 5. The pocket 4 and groove or chamber 5 comprise part of

the main features of my present improvements as distinguished from earlier permutation padlocks.

Rotatably mounted on the body 1 are active tumblers 6, 7, 8, and located intermediate these tumblers are inactive or false tumblers comprising rings 9 serving as a mounting for outer bands 10. The purpose of the rings 9 and bands 10 is to mislead as they exert no locking action on the shackle 11 nor have anything to do with the arrangement of the combination but they are provided with numerals, as shown in Fig. 1, to make the lock that much harder to open.

The shackle may be made in a single U-shaped piece having one leg 11 adapted to extend into the body through a notch 12 in the head 2 and into the groove 3 and pocket 4, the other, shorter, leg 13 having its end adapted to be received in a locking depression 14 in the head 2, or, the shackle may be provided with a joint 15. Both forms of shackle are intended to be covered by my claim. The provision of the joint 15 is of advantage in enabling the shackle to be swung down as shown in dotted lines in Fig. 2. On the other hand, if the shackle is made in a single piece, without the joint 15, it is necessary to turn the shackle on the leg 11 as an axis to cause the leg 13 to clear the head 2.

The shackle is provided with notches 16 to receive the tumblers 6, 7, 8, to thereby lock the shackle as shown in Fig. 3. The tumblers, however, are provided with notches 17 on their inner surface which, when brought into register with the leg 11 of the shackle, permit the shackle to be drawn upwardly. In order to bring about this condition it is necessary to relatively arrange the tumblers 6, 7, 8, to carry out the proper combination. This combination is shown in Fig. 1, where the head 2 is provided with a mark or line 18; the numeral 3 on the tumbler 6 is opposite the notch 17 in that tumbler; the tumbler 7 is provided with a line or mark 19 opposite the notch 17 of said tumbler; the numeral 7 of tumbler 8 is opposite the notch 17 of said tumbler. Consequently when the numerals 3 and 7 of tumblers 6 and 8 are in vertical alignment with the marks 18 and 19, the shackle is released as shown in Fig. 2 and may then be pulled out.

To prevent the shackle from being drawn out beyond a certain limit necessary to either

turn or swing it, according as it is rigid or has joint 15, I provide a lug 20 on the end of the leg 11; this lug and the end of leg 11 are received in the recess or chamber 4 when the lock is in locked condition as shown in Fig. 3. When the shackle is unlocked and is pulled out, the lug 20 is received in the channel 5 and as this channel has an over-hanging shoulder 5^a, the shackle cannot be drawn out after the lug 20 engages said shoulder. If the shackle is turned on the longitudinal axis of the leg 11, the lug 20 turns into the recess 5.

I claim:

15 In a permutation padlock, the combination with a cylindrical body having enlarged heads at its ends and a longitudinally extending groove in its side, of a plurality of peripherally exposed annular tumblers each hav-

ing an internal notch, said tumblers being 20 rotatably mounted on said body between the heads thereof, and a shackle having a leg 25 slideable in said groove and adapted to be locked by said tumblers, or released when their notches register with the groove afore- 30 said, said leg being provided with a lug at its inner end, there being provided in the body a pocket to loosely receive said lug and a shoulder overhanging said pocket, said pocket permitting the leg to be slid length- 35 wise of itself and the shoulder serving as a stop to engage the lug and prevent complete detachment of the shackle from the body, and peripherally exposed annular false tumblers associated with the locking tumblers but having no locking action on the shackle.

In testimony whereof I affix my signature.

FREDERICK A. DURBIN.
